Primary Examiner — Kevin K Rudzinski*Assistant Examiner* — Amber J Rabie(74) Attorney, Agent, or Firm — Banner & Witcoff, Ltd.(57) CLAIM

The ornamental design for a shirt, as shown and described.

DESCRIPTION

FIG. 1 is a side view of a shirt showing my new design; FIG. 2 is a rear perspective view thereof; FIG. 3 is a rear view thereof; FIG. 4 is an opposite side rear perspective view thereof; and, FIG. 5 is an enlarged view of the claim as shown in FIG. 2 with environment removed for clarity purposes.

The broken line immediately adjacent to and surrounding the photographic area defines the peripheral bounds of the claimed design and forms no part thereof. The broken lines depicting the remainder of the shirt form no part of the claimed design.

1 Claim, 5 Drawing Sheets(56)
